Primary Examiner—Mitchell Siegel(74) Attorney, Agent, or Firm—Bell, Boyd & Lloyd LLC(57) CLAIM

The ornamental design for a golf club head with supports, as shown and described herein.

DESCRIPTION

FIG. 1 is a bottom rear perspective view of one embodiment of a golf club head with supports of my new design, that portion of the golf club head shown in phantom is not part of the design sought to be patented and is provided for environmental purposes only.

FIG. 2 is a right side view of the golf club head with supports of my new design illustrated in FIG. 1, wherein the left side is a mirror image thereof and that portion of the golf club head shown in phantom is not part of the design sought to be patented and is provided for environmental purposes only; and,

FIG. 3 is a bottom plan view of the golf club head with supports of my new design illustrated in FIG. 1, that portion of the golf club head shown in phantom is not part of the design sought to be patented and is provided for environmental purposes only.
